Primary Examiner — Cynthia R Underwood(74) *Attorney, Agent, or Firm* — Scully, Scott, Murphy & Presser, P.C.(57) **CLAIM**

The ornamental design for a rotatable double hook, as shown.

DESCRIPTION

FIG. 1. A side and slightly diagonal view of subject invention

FIG. 2. A side view of the subject invention

FIG. 3. An opposite side view of FIG. 2

FIG. 4. A frontal view of subject invention

FIG. 5. An opposite frontal view of FIG. 4

FIG. 6. A top view of subject invention; and,

FIG. 7. A bottom view of subject invention.

1 Claim, 7 Drawing Sheets(56)
